CHARLES MARCUS, OF NEW YORK, N. Y., ASSIGNOR, BY MESNE ASSIGNMENTS, TO
ECLIPSE MACHINE COMPANY, OF ELMIRA HEIGHTS, NEW YORK, A CORPORATION
OF NEW YORK

ENGINE STARTING APPARATUS

Application filed October 28, 1918, Serial No. 260,048. Renewed August 3, 1927.

This invention relates to starting apparatus and with regard to the more specific features thereof, to means for starting internal combustion engines.

5 One of the objects of the invention is to provide practical and durable means of relatively compact, simple and inexpensive construction for starting a source of power.

10 Another object is to provide means of the above type easy to assemble and apply, efficient in action, convenient in control, and whose operation shall be automatic.

15 Another object is to provide efficient means of the above type of few parts which shall effect proper application of the starting power to the engine under all conditions of operation, and whose action shall be relatively easy on the construction.

20 Other objects will be in part obvious and in part pointed out hereinafter.

25 The invention accordingly consists in the features of construction, combination of elements and arrangement of parts which will be exemplified in the construction hereinafter set forth, and the scope of the application of which will be indicated in the following claims.

30 In the accompanying drawings wherein are shown one or more of various possible embodiments of the several features of this invention, Fig. 1 is a longitudinal view partly in section of the outboard form of one embodiment of my invention, the pinion being shown out of engagement with the flywheel.

35 Fig. 2 is a view similar to Fig. 1, showing the teeth of the gears in butting relation and the mechanism biased to relieve this condition.

40 Fig. 3 is a view similar to Fig. 1 of an inboard embodiment of my invention, and

45 Fig. 4 is a fragmentary transverse sectional view taken along the lines 4-4 and 4¹-4¹ of Fig. 2.

Similar reference characters refer to similar parts throughout the different views of the drawings.

50 Referring now to Figs. 1 and 2 of the drawings, there is shown a fragmentary view of a motor armature 1 of any desired form, and of an armature shaft 2. The shaft is

preferably extended beyond the armature as shown at 3, and has a bearing 4 of any conventional form at its outer end, the shaft preferably having no bearing in the proximity of the armature end shown. The bearing 4 is preferably disposed within a gear housing 5 attached to the yoke 6 of the motor. This gear housing 5 is preferably cut away at one side in the usual manner to expose the driving member which is in form of a pinion 60 for engagement with the engine-driven member which is here a geared flywheel 7.

55 As shown in Figs. 1 and 2, the extended armature shaft preferably has a threaded portion 8 contiguous to the armature, and an unthreaded portion 9 at its free end. The minimum diameter of the threaded portion 8 is preferably substantially the same as that of the unthreaded portion 9, the tops of the 60 threads determining a diameter larger than that of unthreaded portion 9. Mounted on the extended shaft 3, there is a transmission unit 10, consisting of a control member which is in the form of a nut 11 in threaded 65 relation with the threaded portion 8 of the shaft and the pinion 60 in slidable relation to the unthreaded portion 9 of the shaft.

70 The nut and the pinion are preferably connected by a barrel construction 12 having a serrated flange 13 whose serrations preferably fit in the spaces 14 between the teeth of pinion 60, said serrated flange also fitting in a cut away portion 15 on the teeth 16 of the pinion. An annulus 17 is preferably 75 disposed against the interior surface of the flange 13 and against the inner extremities of the pinion teeth as at 18, the hub of the pinion being cut away as at 19, to permit its 80 inner portion to extend over the ends of threads 8, the inner extremity of said hub being upset as at 20 against the beveled opening 21 of annulus 17 to firmly secure the pinion 60, annulus 17, and flange 13 together, 85 so that the pinion 60 and barrel 12 constitute a rigid construction.

Although the specific manner described and shown of securing a barrel to the pinion is preferred, it is to be understood that these elements may be com- 90 95 100

bined into a unitary structure by other means.

The end of the barrel 12, opposite pinion 60, is provided preferably with equi-distant slots 22 extending longitudinally thereof for a substantial portion of the length of the barrel. Fitting within these slots are corresponding equi-distant lugs 23 on outstanding flange 24 of nut 11. By this arrangement it is seen that there can be no substantial relative rotation between nut 11 and pinion 60, both said elements being locked against rotation with respect to the barrel although some relative translation is permitted. Other means may be employed to control the relative movement of the nut and the pinion, but it is to be understood that there are special benefits to be derived from the use of the specific construction shown and described.

Within barrel 12 and concentric therewith, there is preferably a relatively powerful coil compression spring 25, one extremity of which presses against annulus 17 of pinion 60, and the other extremity against flange 24 of nut 11, this spring being preferably under some compression when in the position shown in Fig. 1. The nut is prevented from being urged out of barrel 12 by cap 26 fitting over said barrel and provided with a flange 27 extending over the edge of the exposed face of nut flange 24. As shown in Fig. 4, the flange 27 is provided with equi-distant arcuate slots 28 to permit the cap to be slipped over the upstanding portions 29 on the barrel 12 between which slots 22 are formed. A spring metal split ring 30 is preferably laid upon flange 27 and against the interior of metal portions 29, said portions 29 being preferably provided with slots 31, within which preferably fit integral lugs 32 on ring 30, thus locking the cap onto the barrel and preventing the nut from escaping. This locking construction need not be described in greater detail, as it is not my invention, being described and claimed in a copending application of Joseph Bijur, Serial Number 145,839, filed Feb. 1, 1917.

A stop nut 33 is preferably threaded onto the shaft in proximity to bearing 4 and locked thereto, an integral flange 34 being preferably formed on said stop nut near the end adjoining the bearing. A relatively light coil spring 35 preferably surrounds the shaft, resting against flange 34 at one end, and against the face of pinion 60 at the other, the pinion being formed with a circular shoulder 55 of substantially the same diameter as stop nut 33, this shoulder serving to retain the pinion end of the spring in axial alignment with the end at the stop. The purpose and mode of operation of this spring will be described more fully below. It may here simply be noted that the spring

is of larger diameter than the shaft to permit the pinion to abut the adjoining end of stop 33.

At that part of the extended shaft in proximity to the armature, I preferably provide a stop to prevent the transmission unit from sticking or binding when it is thrown out of mesh. This stop preferably consists of a stop member 36 rigidly attached to the shaft, preferably by friction, said member 36 being preferably provided with a flange 37 extending longitudinally of the shaft. Within the flange 37 and preferably resting against the inner surface of stop 36, I preferably provide a fiber stop washer 38, and fitting against said fiber stop washer, I preferably provide a steel stop washer 39, both said washers 38 and 39 being disposed as described to permit their rotation relative to the stop 36. Washers 38 and 39 are preferably prevented from moving out of position by the use of a lock ring 40 within flange 37.

Surrounding the hub portion of nut 11, I preferably provide a cushion spring washer 41 preferably pressed outwardly by a coil spring 42 also surrounding said hub portion and disposed between flange 24 and stop washer 41. The washer is preferably limited from coming off the nut by a lock ring 44.

The embodiment of the invention shown in Fig. 1 is preferably assembled as follows. The transmission unit 10 is first put together as a separate article of manufacture. The compression spring 25 is first slipped into the barrel 12 which was previously attached to the pinion. The nut 11 is then slipped into the barrel, lugs 23 being made to register with slots 22. The cap 26 is then slipped over the barrel preferably compressing spring 25 and the lock ring 30 placed in position in the obvious manner already described in the above identified co-pending application. Thereupon spring 42 and washer 41 are slipped over the hub of the nut 11 and lock ring 44 is placed in position.

Referring now to the motor with its extended shaft 3, the stop 36 and its associated parts being assumed in position, the entire transmission unit 10 above described is slipped over the free end of the shaft, nut first, the nut upon reaching the threaded portion 8 being threaded thereon, the barrel trailing behind, and the pinion being thereby slipped along the unthreaded portion 9 of the shaft. Thereupon the coil spring 35 is placed in position and stop nut 33 is threaded and locked onto the shaft. The gear housing 5 may then be put into position and the entire unit assembled on the engine for use.

If the transmission unit 10 were limited in coming into mesh by means in the interior of said unit, for instance, if it were arrested by a stop abutting the nut at the limit of its

travel, it is obvious that the presence of such stop may render it difficult, if not impossible, to place a previously assembled transmission member upon the shaft as a unit.

5 In Fig. 3 I have shown an inboard form of my invention. In this figure corresponding parts bear the same reference numerals as in Figs. 1 and 2 except that such numerals are primed. In this form the unthreaded portion 9¹ of the shaft is contiguous to the motor and the threaded portion 8¹ is at the outer or free end. To render possible a ready assembly of the construction, by placing the entire transmission member 10¹ upon 10 the shaft as a unit, as in the case of the embodiment shown in Figs. 1 and 2, the interior diameter of pinion 60¹ and the cooperating diameter of shaft portion 9¹, are made slightly larger than the greatest diameter of 15 the threaded portion 8¹. Otherwise the unit 10¹ is substantially identical with unit 10. As is usual in inboard transmissions of the screw shaft type, the outer bearing is preferably dispensed with. The stop 36¹ is 20 generally similar to stop 36 but is locked onto the outer end of the shaft, a nut 45¹ being preferably locked to the extreme end of the shaft, and against said stop. In this embodiment elements corresponding to 25 washers 38 and 39 in Figs. 1 and 2, are not shown, the pitch of threads 8¹ being here shown, sufficiently steep to prevent jamming. Although there are special advantages in the form of the invention shown in 30 Fig. 3, it is to be understood that the outboard form, particularly as shown in Figs. 1 and 2 is my preferred form.

35 Referring now to Figs. 1, 2 and 3, the operation is substantially as follows. The motor being started, the inertia of the transmission unit 10 is such as to make it lag behind the rotating shaft, and the nut therefore moves forward in the well-known manner, pushing the pinion 60 into mesh through spring 25. When the position of full mesh 40 has been reached, pinion 60 and stop 33 abut end to end, spring 35 being compressed. Thereupon the nut 11 is held against rotation by barrel 12 and pinion 60, which pinion in turn is held by the resistance of the 45 engine to cranking. The nut 11 therefore continues to travel along the threaded shaft compressing the spring 25 against pinion 60, which in turn is pressed against stop 33, 50 until the nut reaches the bottoms 46 of slots 22. The nut being then limited from further longitudinal movement with respect to the shaft is compelled to rotate with the shaft, to drive barrel 12 by the action of its 55 lugs 23 and through the barrel to drive the pinion, thus cranking the engine.

It is to be noted that in the action of compressing spring 25, the gradually increasing resistance of the spring causes the nut to be 60 gradually tightened upon the threaded shaft

and thus to transmit a gradually increasing torque, until the nut reaches the bottoms 46 of slots 22 when the entire torque of the motor is transmitted to crank the engine, thus securing substantially shockless action.

65 If instead of the method just described, it be attempted to secure shockless operation by the use of a yielding driving member such as a torsion spring or the like, interposed between the motor and the pinion, not only would the necessity of frequent repair and replacement be likely to arise, but the construction would generally be longer and 70 bulkier.

75 After the engine has started under its own power, it causes pinion 60 to rotate faster than the motor driven shaft, imparting an equal rate of rotation to the nut 11, which thereupon overruns the threaded portion of the shaft 8 drawing the pinion out of mesh 80 with the flywheel. The shock of going to out of mesh position is relieved by washer 41 striking the edge of flange 37 compressing coil spring 42 which acts as a buffer to relieve the shock. The free end of nut 11 85 also strikes the steel washer 39 but sticking is prevented as this washer is free to rotate with respect to the fiber washer 38, which in turn is free to rotate with respect to stop 36. The friction between the two 90 surfaces of the fiber washer and the coacting metal members is relatively low so that in effect this stop unit might serve as a relatively low friction thrust bearing. It is to be noted that instead of the specific thrust bearing construction shown and described, ball bearings or other low friction thrust 95 bearings may be employed to advantage, but it is to be noted that there are special benefits resulting from the use of the specific 100 construction shown and described.

105 During the running of the engine, creeping of the transmission unit into contact with the rotating flywheel gear 7 is prevented by the action of the relatively weak spring 35. This spring while maintaining the transmission unit out of engagement with the flywheel while the vehicle is running, regardless of the grade or roughness of its 110 course, is not sufficiently strong to resist the longitudinal movement of the unit when the motor is started for cranking purposes.

115 Should teeth of the pinion strike teeth of the flywheel end to end when the motor is started, the further translation of the pinion into mesh is of course arrested. Referring to Fig. 2 nut 11 being prevented from rotating because of the stopping of pinion 60, this nut will move longitudinally with respect to the shaft, compressing spring 25. It is found in use that the nut is tightened 120 against the threads to a greater extent than the butting teeth against each other, as the spring is compressed. While the nut is still 125 an appreciable distance from the bottom of 130

slots 46, it will have been tightened upon the threaded shaft by virtue of compression of spring 25, with sufficient force to substantially cease movement with respect to said shaft. When the nut has reached substantially the position shown in Fig. 2, it will therefore rotate slightly with the threaded shaft causing the pinion to rotate slightly, thereby overcoming the butting, whereupon compressed spring 25 rapidly expands urging the pinion substantially into full mesh. The engine member then holding the pinion against further rotation, and the nut 11 being in turn held against rotation, this nut will continue to move longitudinally along the shaft until it reaches the bottoms 46 of slots 22, whereupon the nut is compelled to rotate with the shaft, and the action proceeds in a normal manner as above described. Thus the compression spring 25 upon butting of teeth not only serves to tighten the transmission unit with respect to the threaded shaft to compel rotation, but after such tightening and proper registry of teeth, it snaps the pinion into mesh with the gear by virtue of its expansive force, resulting from its initial compression shown in Fig. 1 with the superadded compression shown in Fig. 2.

If instead of my compression spring a torsion spring were employed to relieve the condition of butting, it is to be noted that such torsion spring would impart no substantial longitudinal thrust to the pinion after the teeth have been brought into proper registry, and consequently the rotative impulse on the pinion, imparted by the motor, may be so much larger than the longitudinal impulse toward full mesh, imparted by the torsion spring, that a destructive rasping of the teeth is likely to result, by the rapid turning of the ends of the pinion teeth against the ends of the flywheel teeth.

A detailed description of the operation of Fig. 3 is unnecessary as this operation is obvious from the above account.

Another important feature of the invention is a provision of means to prevent "hunting" of the driving member. When cranking a four-cylinder gas motor, for example, by means of an electric motor, it will be noticed that the fly-wheel of the gas motor revolves with a velocity which is not uniform during any one revolution and this is due to the fact that at the compression points there is a return of energy imparted to the flywheel which will cause, during a small interval, a small acceleration which is imparted then to the pinion of the electric motor. This acceleration will be imparted by way of barrel 12 to nut 11, causing the nut to overrun the thread 8 in a direction away from mesh. As the nut moves towards this out of mesh position, it travels within slots 22, which for this opera-

tion constitutes a lost motion connection between the nut and the pinion. Before the nut has reached flange 27, the accelerating tendency of the engine will have ceased, and the nut will again move toward the bottoms of slots 22 as shown at 46, and this action will be repeated. Thus, during cranking action the nut may "hunt" back and forth within slots 22, but pinion 60 throughout such action remains in full mesh with flywheel 7. This "hunting" action occurs more particularly in engines with a small number of cylinders, such as four-cylinder engines. As the number of cylinders of an engine is increased, the greater smoothness of resistance to cranking results in a greatly diminished "hunting" action, and in engines of a relatively large number of cylinders, this "hunting" tendency may be imperceptible.

By providing lost motion between the nut and the pinion in the construction above described, I avoid any tendency of the pinion to "hunt". Of course other means embraced within the scope of my invention might be employed for this purpose, but the above-described construction is the preferred form. If no lost motion were provided between the nut and the pinion for moving from the cranking position, or if the pinion were directly threaded on the shaft, it is obvious that when "hunting" does take place the pinion itself will "hunt", with consequent noisy operation and damage to the teeth.

Although I have shown a starter of the direct acting type, it is to be understood that my invention is not confined to such construction but may be adapted to a geared connection with the starting motor. It is however to be noted that there are special advantages inherent in the specific construction shown and described.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. An engine starter including a rotatable shaft, a driving member mounted thereon and adapted to engage and drive a member of the engine to be started, a control member also mounted on the shaft and adapted to

control the position of the driving member and to drive it, and means whereby the control member urges the driving member into cooperation with the engine member 5 and then transmits a gradually increasing torque to such driving member and thence to the engine member, such means including a barrel separate from but connected rigidly with said driving member and loosely with 10 said control member for positive rotary movement therewith and for relative movement of such control member with respect to the barrel.

2. An engine starter including a rotatable 15 shaft, a driving member mounted thereon and adapted to engage and drive a member of the engine to be started, a control member also mounted on the shaft and adapted to control the position of the driving member 20 and to drive it, and means whereby the control member urges the driving member into cooperation with the engine member and then transmits a gradually increasing torque to such driving member and thence 25 to the engine member, such means including a barrel separate from but connected rigidly with said driving member and loosely with said control member for positive rotary movement therewith and for relative movement 30 of such control member with respect to the barrel and also including a coiled spring arranged within the barrel and between said driving and control members.

3. An engine starter including a rotatable 35 shaft, a driving member mounted thereon and adapted to engage and drive a member of the engine to be started, a control member also mounted on the shaft and adapted to control the position of the driving member 40 and to drive it, and means whereby the control member urges the driving member into cooperation with the engine member and then transmits a gradually increasing torque to such driving member and thence 45 to the engine member, such means including a barrel operatively connected at one end with the driving member and having longitudinal slots at its other end, and said control member having projections fitting into 50 and traveling in such slots.

4. In a starter for internal combustion engines and the like, in combination, a rotatable driving shaft, having a threaded portion, and a smooth portion, a pinion on said 55 smooth portion, adapted to mesh with an engine gear, a nut cooperating with said threaded portion, a stop adapted to coact with said pinion for preventing further translation thereof when in mesh with said gear, and a barrel separate from but cooperating with said pinion and said nut to compel said members to rotate as a unit 60 after said stop has arrested said pinion, said nut and pinion having relative movement 65 with respect to each other.

5. In a starter for internal combustion engines and the like, in combination, a shaft having a threaded portion, and a smooth portion, a pinion on said smooth portion, adapted to mesh with an engine gear, a nut 70 cooperating with said threaded portion for translation exceeding that of the pinion, a coil spring interposed between said nut and said pinion, a stop coacting with said pinion for preventing further translation 75 thereof when in mesh with said gear, and a barrel enclosing said spring, and connecting said pinion and said nut, said barrel being rigidly connected with one of said latter members, and limited against rotation with respect to the other.

6. In apparatus of the character described, in combination, a shaft, a pinion on said shaft, adapted to mesh with an engine gear, a nut threaded on said shaft, adapted 85 upon rotation of said shaft to urge said pinion into mesh with said gear, a stop for limiting the translation of said pinion when in mesh, means for tightening said nut on said shaft after said mesh, and a barrel 90 rigid with said pinion and connected to said nut to permit substantial translation thereof, after said stopping of the pinion and to prevent relative rotation.

7. In apparatus of the character described, 95 in combination, a motor driver shaft, a pinion in slidable relation to said shaft, and adapted to mesh with a gear, a nut threaded on said shaft, adapted for translation substantially exceeding that of the pinion and upon starting of said motor to urge said pinion into mesh with said gear, a coil 100 spring between said pinion and said nut, a stop for limiting the translation of said pinion when in mesh, a barrel rigid with said pinion, said barrel having guides, and said nut having means cooperating with said guides, to permit translation of said nut with respect to said barrel and to prevent relative rotation.

8. In apparatus of the character described, in combination, a motor, a driving member adapted to cooperate with an engine-driven member, a member movable with respect to said motor upon starting thereof, 115 to urge said driving member into cooperation with said driven member, a spring between said movable and driving members, and a barrel connecting said movable member to said driving member, said barrel having means to permit said movable member to be translated with respect to said driving member, after said cooperation, and to compel rotation of said driving member with said movable member.

9. In apparatus of the character described, in combination, a shaft, a driving pinion on said shaft, adapted to mesh with an engine gear, a nut threaded 120 on said shaft, a spring between said nut and 125

- said pinion, a stop on said shaft arresting said pinion when in full mesh with said gear, and a barrel connected with said pinion, and having longitudinal slots cooperating with said nut, whereby after said pinion reaches said stop, said nut will move along said slots and compress said spring, gradually tightening itself on said shaft, and then rotating therewith to turn said pinion.
10. In apparatus of the character described, in combination, normally disconnected transmission means, a shaft including a smooth and threaded part driven by said motor, said transmission means including a pinion on said smooth part, a nut cooperating with said threaded part and a coil spring interposed between said nut and said pinion, a stop on said shaft for said transmission means, contacting said pinion when in mesh, and a barrel connecting said nut and said pinion, to prevent relative rotation of said members, said barrel and said nut having interfitting parts to permit said nut to approach said pinion after meshing, compressing said spring.
11. In apparatus of the character described, in combination, a shaft, a transmission adapted to be mounted on said shaft as a unit, said transmission including a driving pinion, a shifting nut threaded on said shaft, a coil spring between said nut and said pinion, and a barrel connecting said nut and said pinion, and preventing relative rotation therebetween,—and a stop on said shaft adapted to contact said pinion to limit the translation of said transmission when in operative relation.
12. As an article of manufacture, an automatic transmission member for engine starters, for mounting as a unit on a shaft, said transmission comprising a pinion, a nut, an interposed spring, and a barrel surrounding said spring and connecting said pinion and said nut, to prevent relative rotation, and to permit some relative translation.
13. As an article of manufacture, an automatic transmission member for engine starters, for mounting as a unit on a shaft, said transmission comprising a pinion, a nut, an interposed coil spring, and a barrel surrounding said spring, connected to said pinion and interfitting said nut to prevent relative rotation between said pinion and said nut and to permit some relative translation.
14. In an engine starter, in combination, a shaft, threaded for a part of its length, a transmission member, including a shifting nut, a driving pinion, a coil spring interposed between said nut and said pinion, and a barrel enclosing said spring and connecting said nut and said pinion to prevent relative rotation, and to permit some relative translation,—whereby said transmission member may be placed as a unit on said shaft with said nut on said threaded portion,—and a stop to engage said pinion when in driving position.
15. In apparatus of the character described, in combination, a shaft, a driving pinion mounted on said shaft, adapted to mesh with an engine gear, a nut threaded on said shaft, a coil spring interposed between said nut and said pinion, and a barrel connecting said nut and said pinion, to prevent relative rotation and to permit some relative translation, whereby should teeth of said pinion and said gear meet end to end, said nut will approach said pinion, compressing said spring and thereby causing more tightening of said nut on said shaft than of said teeth against each other.
16. In apparatus of the character described, in combination, a shaft threaded along a portion of its length, which threads are integral with a transmission member, including a nut, a pinion and a barrel connecting said latter members to prevent relative rotation, said nut having a minimum inner diameter slightly larger than the shaft diameter, whereby said transmission may be slipped onto the unthreaded end of said shaft, nut first, said nut then cooperating with the threaded portion, said pinion following over the unthreaded portion,—and a stop secured to the unthreaded portion, to be abutted by said pinion when in meshing position.
17. In a starter for engines, in combination, an engine-driven element, a motor, a driving member connected to said motor adapted to cooperate with said driven member, a device affected by the starting of the engine under its own power to automatically bring about disengagement between said driving member and said driven element, and a barrel having a lost motion connection with one of said members whereby "hunting" of said driving member is avoided during the cranking operation.
18. In a starter for gas engines and the like, in combination, a rotatable driving shaft, a pinion mounted thereon, a nut threaded on said shaft and a barrel connecting said pinion and said nut, said barrel having means to prevent relative rotation of said nut and said pinion, and means to permit said nut to move longitudinally of said barrel with respect to said pinion whereby "hunting" of said pinion is prevented during cranking.
19. In a starter for gas engines and the like a combined shifting and starting member including; a motor driven element and a driving gear slidably carried thereon, a drum supported at one end on said gear, a rigid member supporting and slidably connecting the other end of the drum to the motor driven element, a spring within the drum between the gear and the rigid mem- 130

- ber, a stop on the motor driven element and a spring between said stop and the rigid member for the purpose described.
20. A drive for engine starters comprising a rotatable screw shaft, a driving member mounted for longitudinal and rotary movement with relation to the shaft and rotary movement therewith, a screw member mounted for longitudinal movement on said shaft and controlling the relative movements of the driving member, and a driving connection established between the said screw and driving members after the driving member has moved to its limit in one direction, by final longitudinal movement of the screw member.
21. A drive for engine starters comprising a rotatable screw shaft, a driving member mounted for longitudinal and rotary movement with relation to the shaft and rotary movement therewith, a screw member mounted on said shaft and controlling the relative movements of the driving member, a driving connection established between the said screw and driving members after the driving member has moved to its limit in one direction by final longitudinal movement of the screw member and a spring for cushioning the establishment of the driving connection.
22. An engine starter including a rotatable shaft, a driving member adapted to engage and drive a member of the engine to be started, a control member mounted on the shaft and adapted to control the position of the driving member and to drive it, and means whereby the control member urges the driving member into cooperation with the engine member and then transmits a gradually increasing torque to such driving member and thence to the engine member, such means including a barrel operatively connected with the driving member and with the control member and having a relative movement with respect to the control member.
23. An engine starter including a rotatable shaft, a driving member adapted to engage and drive a member of the engine to be started, a control member mounted on the shaft and adapted to control the position of the driving member and to drive it, and means whereby the control member urges the driving member into cooperation with the engine member and then transmits a gradually increasing torque to such driving member and thence to the engine member, such means including a barrel operatively connected with the driving member and with the control member and having a relative movement with respect to the control member, and a spring resisting said relative movement.
24. An engine starter including a rotatable screw shaft, a pinion adapted to engage and drive a member of the engine to be started, a control member adapted to control the position of the pinion and to drive it, a barrel operatively connected with the pinion and with the control member and having a relative movement with respect to the control member, and a spring resisting said relative movement.
25. An engine starter including a rotatable shaft, a driving member mounted to slide thereon and having a limited range of longitudinal movement thereon when slid to engage a member of the engine to be started, a control member adapted to control the position of the driving member and to drive it and mounted on the shaft for longitudinal movement thereof and rotary movement therewith, said control member having a range of longitudinal movement in excess of that of the driving member, and operating means connecting between the driving member and the control member, said operating means and said control member having a lost motion connection between them.
26. An engine starter including a rotatable shaft, a driving member adapted for translation to engage and rotation to drive a member of the engine to be started, a control member for translating and driving said driving member having operative connection with said shaft for automatic translation with respect thereto and adapted to be driven therefrom, and operative connections between said driving member and said control member involving means for preventing hunting action of the driving member, said connections including a barrel having translational lost-motion connection with one of said members.
27. An engine starter including a driving member adapted to engage and drive a member of the engine to be started, a rotatable shaft, a control member operatively associated with said shaft for automatic translation relative thereto and to be driven therefrom; connected with the driving member and adapted to control the position thereof and to drive it, and means whereby the control member urges the driving member into cooperation with the engine member and then in continuance of its translation transmits a gradually increasing torque to such driving member and thence to the engine member.
28. An engine starter including a driving member adapted to engage and drive a member of the engine to be started, a rotatable shaft, a control member operatively associated with said shaft for automatic translation relative thereto and to be driven therefrom; connected with the driving member and adapted to control the position thereof and to drive it, and means whereby the control member urges the driving mem-

ber translationally into cooperation with the engine member and then in continuance of its translation transmits a gradually increasing torque to such driving member and thence to the engine member, said two members having a lost-motion connection between them.

29. An engine starter including a driving member adapted to engage and drive a member of the engine to be started, a rotatable shaft, a control member adapted to position and drive the driving member operatively connected with said shaft to be automatically translated with respect thereto and driven therefrom, and a connector between the two members having a lost-motion provision whereby hunting of the driving member is prevented.

30. An engine starter comprising a rotatable shaft, a driving member adapted for limited translation to fully engage and rotation to drive a member of an engine to be started, a control member automatically operable by said shaft for translation with respect thereto and to be driven therefrom, and translationally-yielding lost-motion operating-connections between said control and driving members adapted for substantial yield after the driving member reaches fully-engaged position whereby substantial hunting retreat of the control member does not retract the driving member.

In testimony whereof, I have signed my name to this specification this 20th day of August, 1918.

CHARLES MARCUS.
